UNITED STATES PATENT OFFICE

HAROLD D. NORTH, OF CLEVELAND, OHIO

MOTION PICTURE SCREEN

Application filed December 30, 1930. Serial No. 505,506.

The present invention relates to motion picture screens suitable for use with small portable projecting machines such as commonly used for displaying motion pictures 5 in homes, school rooms and the like, such screens being commonly provided with specially prepared reflecting surfaces in the form of a thin more or less frangible coating which should be protected against accidental 10 scratching or marring in the handling thereof and against griming during the intervals in which the screen is not in use.

The present invention has for its object to provide a screen having a mounting frame 15 which is attractive in appearance, which is of simple and inexpensive construction and which provides a housing for the screen protecting the reflecting surface against damage and against griming by handling or by collection of dust thereon.

A further object is to provide a screen mounting frame in which the screen is rigidly supported and which is provided with a removable shield for the screen in the form 25 of an opaque panel which fits closely within the frame over the reflecting surface of the screen, and further to provide means for detachably securing the shielding panel in the frame in front of the screen and spaced therefrom.

A further object is to provide a mounting 30 for the shielding panel within the frame such that the panel may have a close fit within the frame but may be swung out from the recess of the frame and lifted clear thereof by a single movement.

With the above and other objects in view the invention may be said to comprise the portable motion picture screen as illustrated 40 in the accompanying drawing hereinafter described, and particularly set forth in the appended claims, together with such variations and modifications thereof as will be apparent to one skilled in the art to which the invention appertains.

Reference should be had to the accompanying drawing forming a part of this specification, in which:

Fig. 1 is a front elevation of a screen embodying the invention;

Fig. 2 is an end elevation of the screen;
Fig. 3 is a vertical section taken on the line indicated at 3—3 in Fig. 1;

Fig. 4 is a bottom plan view of the elastic retaining element on the frame which releasably engages the shielding panel to hold the same in the frame;

Fig. 5 is a section taken on the line indicated at 5—5 in Fig. 1;

Fig. 6 is a section taken on the line indicated at 6—6 in Fig. 1;

The screen supporting frame, as illustrated in the accompanying drawing, is a frame of rectangular form composed of stiles 1 and upper and lower rails 2 and 3, and this frame is adapted to be supported in upright position by means of a pair of pedestals 4 each in the form of a bar pivoted intermediate its ends to the bottom of the rail 3 and adapted to be moved from a position in which the bar is in the plane of the frame to a position in which the bar extends at right angles to the frame, the pedestals 4, when positioned at right angles to the frame, forming a stable support for the frame.

The screen proper consists of a suitable plate 5 preferably of metal having a coating of suitable reflecting material applied to the front face thereof. The metal plate 5 is held against the front face of a rigid backing panel 5^a which is secured to the rear face of the supporting frame, preferably with its marginal edges flush with the outer edges of the stiles 1 and rails 2 and 3 of the frame. Molding strips 6 are secured to the interior faces of the stiles 1 and rails 2 and 3 closely adjacent the plate 5 and a border strip 7 is secured between the molding 6 and the plate 5, the border strip 7 preferably projecting inwardly a short distance beyond the inner edges of the molding 6. Strip 7 and molding 6 together with the supporting frame provide a border around the reflecting screen.

The molding 6 is spaced inwardly from the front face of the supporting frame and the stiles 1 and rails 2 and 3 of the frame have flat inner faces between the forward edges of the molding strip 6 and the front face of the frame. Immediately in front of the forward edge of the molding strip 6 which extends

across the interior of the frame at the bottom thereof, the rail 3 is provided with a channel 8 extending throughout the length thereof. The top rail 2 is provided on its under side 5 and midway between its ends with a transverse recess 9 extending inwardly from the front face of the rail to the molding in which is mounted an elastic retaining element in the form of a U-shaped spring 10, one arm 10 of which lies on the bottom of the recess and is secured by screws 11 to the rail 2.

In order to protect the screen during intervals in which the screen is not in use, an opaque shielding panel 12 is provided which 15 fits within the supporting frame forwardly of the molding strip 6 and which is releasably held against the molding strips 6 which serve as spacer strips for holding the shielding panel in a position spaced from the reflecting screen. On its outer face the shielding panel 12 is provided with a marginal molding 13 which is positioned with its outer edges flush with the edges of the panel along the top and along opposite ends of the 20 panel. The molding 13, however, is spaced upwardly a short distance from the bottom edge of the panel as shown in Fig. 3 of the drawing. The width of the shielding panel 12 corresponds to the interior width of the 25 frame while the height of the panel 12 is somewhat in excess of the interior height of the frame. When the panel is in place in the frame the molding 13 across the bottom portion of the panel rests on the top face 30 of the bottom rail 3 and the projecting edge of the panel extends into the channel 8. The panel 12 has a close fit between the stiles 1 and very little clearance is necessary between the top of the panel and the top rail 2 of the 35 frame to permit the panel to be entered into the recess of the frame by entering the lower edge of the panel in the channel 8 and swinging the top of the panel inwardly, or to be removed from the frame by swinging the top 40 of the panel outwardly. In entering the panel 12 into the frame and in withdrawing the panel from the frame the outer corner of the lower molding 13 provides a fulcrum upon which the panel pivots. This corner 45 is spaced outwardly from the channel 8 and can slide outwardly as the upper edge of the panel is swung outwardly so that the channel 8 needs but slightly greater width than the thickness of the panel 12. The upper edge 50 of the panel 12 is at a considerable distance from the axis about which the panel swings so that in moving through the small angle necessary to bring the top of the panel clear of the top rail 2 of the frame, the top edge 55 of the panel has a very slight upward movement.

Midway between the ends thereof, the molding 13 at the top of the panel 12 carries a stud 14 which may be the head of a screw 60 secured to the molding, and this stud en-

gages with the free arm 15 of the U-shaped spring 10 as the panel is moved into the frame, engaging the depression 16 formed in said arm of the spring when the panel reaches its fully entered position in engagement with the molding or spacing strips 6. 70

Adjacent opposite ends thereof, the molding 13 across the top of the panel 12 is provided with finger receiving notches or recesses 17 which provide means for grasping 75 and pulling the top of the panel outwardly. When such a pull is exerted on the panel the elastic spring retaining element 10 yields permitting the stud 14 to move outwardly and as the top of the panel is moved outwardly the panel rocks about the front corner of the bottom molding strip 13 and the portion of the panel projecting into channel 8 is moved upwardly until the top of the panel has been shifted to a position clear of the top rail 2, whereupon continued movement of the panel causes the same to be lifted clear of the screen supporting frame. As shown in Fig. 4, the spring 10 tapers toward 80 the end of the outer arm 15 thereof so that 85 access is provided to the fastening screws 11 which secure the spring to the rail 2.

It will be apparent that the present invention provides a portable motion picture screen in which the reflector is mounted in 95 a rigid supporting frame and protected by a rigid backing panel, the frame being also provided with a shielding panel which has a close fit therein, so that the screen may be subjected to considerable rough usage in 100 handling and storing without damaging the frangible reflecting surface of the screen, and the screen may be stored for long periods of time without griming of the reflecting surface by accumulations of dust. 105

It will further be apparent that the detachable shielding panel is securely held in place in the frame since the entire panel and the panel retaining element lie entirely within the plane of the front face of the supporting frame, and any impact on the surface of the panel will be taken up by the rigid molding strips 6 which act as stops or spacers against which the panel rests and will not tend to dislodge the panel from the 110 frame. 115

Furthermore, it is to be understood that the particular form of apparatus shown and described, and the particular procedure set forth, are presented for purposes of explanation and illustration and that various modifications of said apparatus and procedure can be made without departing from my invention as defined in the appended claims. 120

What I claim is:

1. A portable motion picture screen comprising a panel having a reflecting screen on its front face, a frame secured to the margin of said panel and forming a border for said screen, the bottom portion of said frame hav- 125 130

- ing a channel on the interior thereof extending parallel with the face of the panel and spaced outwardly therefrom, removable shielding panel fitting within the frame and 5 having an edge portion extending into said channel, and a yielding retaining element carried by the frame and engaging the upper edge of the shielding panel for holding the same in place in the frame. 10 2. A portable motion picture screen comprising a panel having a reflecting surface on its front face, a frame secured to the margin of said panel and forming a border for said reflecting surface, said frame having a molding around the interior thereof closely adjacent the panel and spaced from the front face of the frame, said frame having a channel extending across the bottom thereof along the forward edge of said molding, a shielding 20 panel of a width corresponding to the interior width of said frame and a height in excess of the height of the frame, said panel fitting in said frame outwardly of said molding with its lower edge in said channel, and a yielding retaining element carried by the frame and engaging with the upper edge of the shielding panel for holding the panel in engagement with said molding. 25 3. A portable motion picture screen comprising a panel having a reflecting surface on its front face, a frame secured to the margin of said panel and forming a border for said reflecting surface, said frame having a molding around the interior thereof closely adjacent the panel and spaced from the front face of the frame, said frame having a channel extending across the bottom thereof along the forward edge of said molding, a shielding 30 panel of a width corresponding to the interior width of said frame and a height in excess of the height of the frame, said panel fitting in said frame outwardly of said molding with its lower edge in said channel, and a yielding retaining element carried by the frame and engaging with the upper edge of the shielding panel for holding the panel in engagement with said molding. 35 4. A portable motion picture screen comprising a panel having a reflecting surface on its front face, a frame secured to the margin of said panel and forming a border for said reflecting surface, said frame having a molding around the interior thereof closely adjacent the panel and spaced from the front face of the frame, said frame having a channel extending across the bottom thereof along the forward edge of said molding, a shielding 40 panel of a width corresponding to the interior width of said frame and a height in excess of the height of the frame, said panel fitting in said frame outwardly of said molding with its lower edge in said channel, a marginal molding secured to the front face of the shielding panel, the outer edges of which are flush with the edges of the panel along the sides and across the top of the panel and spaced from the edge of the panel across the bottom of the panel, a stud projecting from 45 the outer edge of said molding substantially midway between the ends of the panel at the top thereof, and an elastic retaining element carried by the frame and engaging said stud to retain said shielding panel in the frame. 50 5. A portable motion picture screen comprising a backing panel, a frame secured on the margin of the front face of said panel, and forming a forwardly projecting border, said frame having spacer strips on the interior thereof closely adjacent the panel, said strips being spaced inwardly from the front face of the frame, a shielding panel fitting within the frame outwardly of said spacers, releasable means for holding said shielding panel against said spacer strips, and a reflector lying upon and covering the front 55 face of the backing panel within said frame, said reflector being protected by the backing and shielding panels and being exposed upon removal of the shielding panel. 6. A portable motion picture screen comprising a backing panel, a frame secured on the margin of the front face of said panel, and forming a forwardly projecting border, said frame having spacer strips on the interior thereof closely adjacent the panel, said strips being spaced inwardly from the front face of the frame, said frame having a channel at one side thereof extending along the forward edge of a spacer strip, a shielding 60 panel fitting within the frame outwardly of the spacers and having one edge fitting in said channel, elastic retaining means carried by the frame and engageable with the edge of the panel opposite that received in said channel, and a reflector lying upon and covering the front face of the backing panel within said frame, said reflector being protected by the backing and shielding panels and being exposed upon removal of the shielding panel. 65 7. A portable motion picture screen comprising a panel having a reflecting screen upon its front face, a frame secured to said panel and forming a forwardly projecting protective border for the screen, a removable shielding panel for covering and protecting said screen fitting within the forward portion of said frame, stops on the interior of the frame forwardly of the screen for engagement with the marginal edges of the 70 75 80 85 90 95 100 105 110 115 120 125 130

shielding panel, to space the same away from the screen, and means for releasably holding the shielding panel in place in the frame whereby the shielding panel may be readily removed to expose the screen or be inserted into the frame to shield the screen.

8. A portable motion picture screen comprising a panel having a reflecting screen upon its front face, a frame secured to said panel and forming a forwardly projecting protective border for the screen, a removable shielding panel for covering and protecting said screen fitting within the forward portion of said frame, stops on the interior of the frame forwardly of the screen for engagement with marginal edges of the shielding panel to space the same from the screen, and retaining means engageable with a marginal edge of said shielding panel for holding said panel in place in the frame, said retaining means being yieldable whereby said shielding panel may be readily lifted out of the frame to expose the screen.

In testimony whereof I affix my signature.
